UNITED STATES PATENT OFFICE

2,192,636

HEATING UNIT

John E. Briggs, Detroit, Mich.

Application March 23, 1937, Serial No. 132,515

7 Claims. (Cl. 126—99)

This invention relates to furnaces and more particularly to an improved hot air furnace structure and to a novel heating apparatus therefor.

An important object of this invention is to provide a novel flue structure for a furnace including a novel control therefor for regulating the heat transfer between the hot combustion gases conducted from the combustion chamber by the flue and the room air which it is desired to heat. 5 The flue is constructed in a novel manner to provide on the one hand a short direct passage for the combustion gases, and on the other hand a long tortuous path for the combustion gases, or any degree between these extremes. Room 10 air which it is desired to heat is passed in surface contact with the flue structure, and the amount of heat transferred from the flue to the room air varies in direct proportion to the extent of the path provided in the flue structure for the 15 conduction of the hot combustion gases. It is possible therefore as a result of this invention to regulate with nicety the degree of heat transfer between the hot combustion gases and the relatively cool room air which it is desired to heat. 20 More specifically, the invention contemplates a flue structure opened at one end for communication with the combustion chamber of the furnace and closed at the other end and provided with a bodily movable baffle dividing the flue into 25 two compartments. The baffle is supported in a novel way in the flue for longitudinal adjustment, and is adapted upon longitudinal adjustment to vary the quantity of hot combustion gases deflected through the compartments of the flue. 30

Another object of this invention is to provide 35 a novel hot air furnace structure. The structure includes a furnace, a surrounding casing and a plurality of exhaust flues associated together in a novel fashion for varying the path of the exhaust gases and thus varying the amount of heat transference between the air in the casing and the exhaust gases in the flues. Provision is made 40 for admitting fresh air to the casing and discharging air warmed therein from the top of the casing. A novel deflector construction is provided within the casing for directing the fresh air admitted thereto into close proximity with the walls of the flues. 45

Other objects, advantages and meritorious features of this invention will appear more fully from the following specification, appended claims and accompanying drawings, wherein:

Fig. 1 is a cross-sectional view of a hot air furnace from front to rear showing the location 50 and construction of the various features of the

invention and the manner in which they cooperate with one another.

Fig. 2 is a front end view of the hot air furnace illustrated in Fig. 1 partly broken away to show the interior construction of the furnace 5 along line 2—2 of Fig. 1.

Fig. 3 is a detail view of the flue construction along line 3—3 of Fig. 2.

Referring more particularly to the drawings, the furnace structure comprises a shell or casing 10 surrounding the furnace proper indicated generally by the reference numeral 12. As is customary, the casing 10 is mounted in spaced relationship to the furnace 12 in order to form an air chamber between these two units. In the embodiment of the invention illustrated herein the casing is spaced from the furnace in the rear and on the opposite sides thereof, the front of the casing and the furnace coinciding so that access may be had to the doors of the furnace. Air is conducted from the rooms of the building in which the furnace is located by an air duct 14 and by means of a fan located in the fan housing 16 this air may be forced into the bottom of the air chamber formed by the casing and the furnace units. The top of the casing is provided with a discharge outlet 18 as shown and any suitable air duct may be connected thereto for conducting the air in the casing to the rooms which it is desired to heat. 20

The furnace unit 12 includes a heating apparatus generally indicated at 20 and a combustion chamber 22 into which the heating apparatus discharges the flames of combustion. As shown in the drawings the bottom of the furnace is provided with a base foundation 24 of any suitable fire resisting material. A circular recess 26 is formed in the front section of this material and the heating apparatus 20 is disposed therein. 30

The hot products of combustion are conducted away from the combustion chamber by a novel system of flues. The top of the combustion chamber is closed off by a plate 28 having a slightly inverted V-formation as best shown in Fig. 2. This plate extends from the front of the furnace to a point slightly spaced from the rear wall 30 of the furnace. A partition 32 rises vertical from this point and forms, in conjunction with the rear wall 30, a passage 34 leading upwardly from the rear of the combustion chamber. Extending from the rear wall 30 to the partition 32 are a pair of oppositely facing, slightly inclined elements 35 and 36 joined together with the top of the plate 28 to form a diamond-shaped air duct 38 as best shown in Fig. 2. Both the rear wall 40 45 50 55

30 and the partition 32 are apertured at the opposite ends of the duct 38 and air rising in the casing 10 can flow through this duct to the front side of the partition 32. The air duct 38 divides 5 the passage 34 into two vertical flues 40 and 42 which diverge slightly around the diamond-shaped air passage 38 as they rise from the combustion chamber and then converge and join together in the upper part of the casing. An ex- 10 haust pipe 44 extending rearwardly from the furnace and casing opens into the vertical flues 40 and 42 at their juncture.

The partition 32 is pierced at three places in the embodiment of the invention disclosed herein to 15 provide circular openings into which the open ends of three horizontal cylindrical flues may be positioned. Obviously, the number as well as the size of these cylindrical flues may be varied to suit different conditions. In the embodiment 20 of the invention disclosed herein a circular opening is provided in the top of the partition 32 opposite the exhaust pipe 44 and two more of such openings are provided below and upon opposite sides thereof, one opening into each vertical flue 40 and 42. The three openings are therefore arranged in triangular formation as 25 Fig. 2 will show.

As previously explained, a cylindrical-shaped flue is supported in each of the three openings in 30 the partition 32. These flues extend forwardly of the partition 32 in horizontal parallel relationship. They therefore form a triangular or pyramidal flue construction in the space above the plate 28 of the combustion chamber. The 35 two cylindrical flues on opposite sides of the partition are numbered 46 and 48. The top cylindrical flue is numbered 50. The top cylindrical flue is preferably of larger diameter than the two lower flues as shown in Fig. 2 in order to accommo- 40 date the products of combustion of both of the vertical flues 40 and 42. The front ends of these cylindrical flues project through the front wall of the furnace 12 where they are supported.

In each of the cylindrical flues is a deflecting 45 element or baffle plate. For each cylindrical flue 46, 48 and 50 the baffle plate is numbered respectively as 52, 54 and 56. The baffle plates are preferably of a width slightly less than the diameter of the flue in which it is positioned and of a 50 length substantially equal to the length of its respective flue. These baffle plates are supported in their respective flues by merely bearing upon the inner wall surfaces of the flues. Since they have a width slightly less than the diameter of 55 their respective flues they extend substantially diametrically across the flue as shown in Fig. 2 and divide the same into upper and lower compartments of almost the same size. The manner of supporting the baffle plates in the cylindrical 60 flues permits them to be adjusted longitudinally therein and, as shown in Fig. 1, they may be adjusted so as to project into the vertical flues 40 and 42 while the front ends of the baffle plates are spaced inwardly from the front end of the 65 cylindrical flues.

Each cylindrical flue is closed at its front end by a removable closure member or door. Two of such doors are shown at 58 and 60 in Figure 1. These doors permit access to the interior of the 70 cylindrical flues and enable one to reach the baffle plates and adjust them longitudinally in their respective flues. These doors also permit one to gain access to the cylindrical flues for cleaning purposes.

75 The operation of the baffle plates 52, 54, and 56

is easily understood from the arrows in Fig. 1 indicating the paths of the burnt combustion gases. When the baffle plates project into the vertical flues 40 and 42 they deflect some of the products of combustion into their respective flues as shown in Fig. 1. As indicated by the arrows, the products of combustion deflected by these baffle plates are directed forwardly through the lower compartment of each cylindrical flue, then upwardly at the forward end thereof and 10 thence rearwardly through the upper compartment of each flue. The amount each baffle plate projects into the vertical flues 40 and 42 determines in like proportion the volume of hot combustion gases its respective cylindrical flue 15 will receive. When the baffle plates project into the vertical flues until they abut or almost abut the rear wall 30 of the furnace, a long tortuous path is provided for conducting all of the hot combustion gases from the combustion chamber 20 to the exhaust pipe 44. However, when the baffle plates are adjusted to positions entirely within their respective flues, the vertical flues 40 and 42 are opened and a short direct path is provided 25 for exhausting the combustion gases rising from the combustion chamber. Obviously, the baffle plates may be adjusted to positions intermediate these two extremes.

The fresh room air directed by the fan into the bottom of the casing 10 rises into surface contact 30 with the heated walls of the furnace and the flues. The degree to which this room air is heated is varied by the area and the temperature of the heating surface with which it comes in contact. Adjustment of the baffle plates in their respective flues will vary the amount of hot combustion gases deflected therethrough and as a result vary the temperature of the walls of these flues and the area of heated surfaces presented to the room air in the casing. Some of the fresh 40 room air enters the diamond-shaped duct 38 and passes into the highly heated area in the center of the triangular formation formed by the cylindrical flues. Some of the fresh room air rises along side of the furnace and thence into contact with 45 the vertical and horizontal flues. In order to direct the greater portion of the air rising in this manner into direct contact with the cylindrical flues, a pair of deflector elements 62 and 64 on opposite sides of the furnace may be provided. The upper ends of these elements are curved inwardly in order to deflect the rising currents of 50 air toward and under the cylindrical flues as shown in Fig. 2. The deflector elements 62 and 64 preferably extend from the front wall to the 55 rear wall of the casing 10.

As shown in the embodiment of the invention illustrated herein, the baffle plates in the cylindrical flues are of slightly less width than the diameter of the flues. The purpose of this construction is to provide openings for the upward escape of gas in case of an explosion or the creation of an undue gas pressure in the combustion chamber in some other manner. In the event such a sudden pressure is created, the baffle plates 65 are able to rise and provide clearances along both of their side edges to permit the escape of the gas and as a result instantly lessen the pressure of gas.

The heating apparatus for the furnace illustrated herein is an oil burner type. It comprises a number of elements associated together to form a mixing chamber shaped in the formation of a bowl having a smaller discharge outlet than the interior thereof. A blower 94 driven by a 70 75

motor 96 delivers air to the burner through air pipes 74 and fuel pipe 82 delivers fuel to the burner from a suitable source. The construction and operation of the burner forms no part of this particular invention other than that a burner of suitable structure is required.

What I claim:

1. A hot air furnace structure comprising, in combination, a casing having an air inlet adjacent the bottom and an air outlet adjacent the top and a communicating connecting air passageway, a furnace within said casing having a combustion chamber and a vertical flue rising vertically from the rear of said combustion chamber, a plurality of horizontally mounted cylindrically-shaped flues opening into said vertical flue and extending forwardly therefrom over the combustion chamber of the furnace, means sealing the forward ends of said horizontal flues, and a baffle plate in each of said horizontal flues mounted for longitudinal slidable movement therein and adapted to project beyond its respective horizontal flue into said vertical flue for the purpose of deflecting exhaust gases rising in said vertical flue into its respective horizontal flue and an air conduit leading from said communicating air passageway through said vertical flue and discharging between said plurality of horizontally mounted flues.
2. A hot air furnace comprising, in combination, a combustion chamber, a pair of spaced vertical flues leading from said combustion chamber for conducting hot combustion gases therefrom and joining at their upper ends to form a common conduit for conducting the combustion gases, a horizontal flue having one end opening into said vertical flues at the point of their juncture, a horizontal flue for each vertical flue having one end thereof opening into its respective vertical flue at a point below the juncture of the vertical flues, a closure member for each of said horizontal flues removably secured to the opposite ends of said horizontal flues and when closed sealing the horizontal flues against the escape of combustion gases therewithin, a plate element in each of said horizontal flues dividing each of the same into upper and lower compartments, said plate elements being longitudinally adjustable in their respective flues and adapted to project varying distances across the passages of said vertical flues to regulate the amount of the combustion gases deflected into the horizontal flues, and a casing surrounding said combustion chamber and said flues having an air inlet adjacent the bottom and an air outlet adjacent the top above the juncture of the vertical flues.
3. A hot air furnace comprising, in combination, a combustion chamber, a pair of spaced vertical flues leading from said combustion chamber for conducting hot combustion gases therefrom and joining at their upper ends to form a common conduit for conducting the combustion gases, a horizontal flue having one end opening into said vertical flues at the point of their juncture, a horizontal flue for each vertical flue having one end thereof opening into its respective flue at a point below the juncture of the vertical flues, a closure member for each of said horizontal flues removably secured to the opposite ends of said horizontal flues and when closed sealing the horizontal flues against the escape of combustion gases therewithin, a plate element in each of said horizontal flues dividing each of the same into upper and lower compartments, said plate elements being longitudinally adjustable in

their respective flues and adapted to project varying distances across the passages of said vertical flues to regulate the amount of combustion gases deflected into the horizontal flues, a casing surrounding said combustion chamber and said flues having an air inlet adjacent the bottom and an air outlet adjacent the top above the juncture of the vertical flues, and deflector elements in said casing causing the air entering said casing to pass in close proximity to the exhaust flues to be heated thereby.

4. A hot air furnace structure including, in combination, a vertical flue for conducting hot combustion gases, a horizontal flue having one end thereof opening into said vertical flue, means for sealing the other end of said horizontal flue against the escape of combustion gases therewithin, a plate having a width slightly less than the transverse dimension of the horizontal flue and a length less than the combined length of the horizontal flue and horizontal dimension of said vertical flue, said plate arranged within said horizontal flue on substantially a horizontal plane dividing the horizontal flue into top and bottom compartments, and supported for slidable movement longitudinally within said horizontal and transversely of said vertical flue and adapted by reason of the fact that its length is less than the combined length of the horizontal and vertical flues to present openings of variable sizes at either or both ends of the plate to regulate the amount of the combustion gas flowing from the vertical flue through the compartments of said horizontal flue, said plate supported within the horizontal flue for vertical movement within the horizontal flue for escape of gas from the lower to the upper compartments within the horizontal flue along the longitudinal margins of the plate.

5. A hot air furnace comprising, in combination, a combustion chamber, a vertical flue for conducting hot combustion gases from said chamber, a horizontal cylindrical flue having one end thereof opening into said vertical flue, a baffle plate of slightly less width than the diameter of said cylindrical flue extending longitudinally therethrough, said baffle plate dividing the flue into upper and lower compartments and being shiftable vertically within the flue to provide for the escape of gas directly from the lower into the upper compartment along the longitudinal edges of the plate.

6. A hot air furnace comprising, in combination, a casing having an air passageway therethrough provided with an air inlet at the bottom and an air outlet at the top, a furnace within said casing having a combustion chamber provided with a vertical exhaust flue, a pair of horizontally spaced horizontal flues superimposing said combustion chamber and each communicating with the vertical flue at one end and closed at its opposite end, and a third horizontal flue superimposing the space between said pair of flues and communicating with the vertical flue at one end and closed at the opposite end, a partition extending from the vertical flue over the combustion chamber spaced below said pair of flues, a baffle plate extending longitudinally through each horizontal flue of said pair dividing the same into communicating upper and lower compartments, an air conduit extending from the air passageway through the casing through said vertical flue into the space above said partition between said horizontal flues, and dividing said vertical flue into two vertical compartments, one of said compartments communicating with one of the hori-

zontal flues of said pair and the other compartment communicating with the other horizontal flue of said pair.

7. A hot air furnace comprising, in combination, a casing having an air inlet at the bottom and an air outlet at the top, a furnace disposed within said casing having an enclosing wall spaced from the side wall of the casing providing an air passageway about the furnace within the 10 casing, said furnace including a combustion chamber having a vertical exhaust flue provided with an outlet, a partition superimposing said combustion chamber, a plurality of horizontal exhaust flues superimposing said partition and each 15 communicating at one end with said vertical ex-

haust flue, a baffle plate extending longitudinally through each horizontal flue dividing the same into communicating upper and lower compartments, said horizontal flues communicating with the outlet of said vertical flue, an air conduit leading from the air passageway in the casing beyond the wall of the furnace through said vertical flue into the space above said partition to discharge air to circulate about said horizontal flues, and baffle plates disposed within the casing 10 spaced outwardly from the furnace wall adapted to direct air into the space above said partition underneath said horizontal flues.

JOHN E. BRIGGS. 15
